UNITED STATES PATENT OFFICE.

BENNY J. WERTHEIMER, OF SAN FRANCISCO, CALIFORNIA.

DESIGN FOR A CASE FOR COIN-CONTROLLED MACHINES.

SPECIFICATION forming part of Design No. 26,684, dated February 23, 1897.

Application filed June 26, 1896. Serial No. 597,086. Term of patent 3½ years.

To all whom it may concern:

Be it known that I, BENNY J. WERTHEIMER, a citizen of the United States, residing in the city and county of San Francisco, State of California, have invented and produced a new and original Design for a Case for Coin-Controlled Machines, of which the following is a specification.

The essential feature of the design is the ornamentation and configuration illustrated and herein described.

In the drawings, Figure 1 is a front elevation of a casing embodying my design, and Fig. 2 is an end view of the same.

The letter A is used to indicate the front plate of the casing, which has a central glass front A', surrounded by an ornamental border B. The end plates B' of the casing have a smooth outer border a and an inner field a'

in imitation of frosted work. The front, back, and end plates rise from a base A², and the front and end plates have a gradual curve from the point 2 to the top. On the front plate, below the glass front, is a plate B², and above the glass front is a frame C. On the glass front at one edge of the same is a plate b³, having a central slot b⁴.

Having thus described my invention, what I claim is—

The design for a casing of coin-controlled machines herein described and shown.

In testimony whereof I affix my signature, in the presence of witnesses, this 5th day of June, 1896.

BENNY J. WERTHEIMER.

Witnesses:

LEE D. CRAIG,
